UNITED STATES PATENT OFFICE

RALPH H. LANGLEY, OF CINCINNATI, OHIO, ASSIGNOR TO THE CROSLEY RADIO CORPORATION, OF CINCINNATI, OHIO, A CORPORATION OF OHIO

LOUD SPEAKER MOUNTING FOR AUTOMOBILE RADIOS

Application filed June 25, 1930. Serial No. 463,774.

My invention relates to a loud speaker mounting and has especial reference to means for mounting a loud speaker in an automobile in whatever place is suitable. In placing 5 radio receiving sets and loud speakers in automobiles, serious difficulties have been encountered in finding a proper method of mounting loud speakers so that they will be held in place and will not vibrate or rattle 10 because of movement of the vehicle or vibration from the engine.

The principal object of my invention is to provide means for mounting a loud speaker in any desired place in an automobile so that 15 it will be held securely in place and will not rattle or vibrate.

While the invention is primarily designed for automobile use, yet it is not limited to this use alone as the same method of mounting may be used on the back or underneath 20 part of radio cabinets having no loud speakers installed therein.

In the particular embodiment of my invention selected for illustration,

25 Figure 1 is a side elevation of a loud speaker mounted on a panel board.

Figure 2 is a bottom plan view of a loud speaker embodying my invention and showing the method of securing the speaker to 30 the element secured to a panel board or other suitable object.

Figure 3 is a section on the line 3—3 of Figure 2, and

35 Figure 4 is a detail of one of the springs or lugs for securing the speaker in place.

The loud speaker 5, which represents any well known design and construction, has on 40 its back, secured thereto by suitable fastenings, as the rivets 6, the clip members 7, each a flat resilient strip with a compound bend forming the base part by which it is secured to the speaker, and a tongue spaced from the speaker back with a space between it and the back open at the end of the tongue. These 45 clip members 7 are arranged in circular series with their tongues all extended in the same circumferential direction. Each tongue has a depression 7' near its free end, toward the speaker back, forming a detent.

50 The plate 8 has radial arms 9, one for each

clip member 7, and has compound bends at the junctions of the arms 9 with the main part of the plate, which is screwed to the vehicle panel board 10 with the arms 9 spaced out therefrom by the bends. The speaker 5 is placed against these arms 9 and rotated until the clip members 7 snap over the respective arms 9, with each arm held snugly between the clip member tongue and the speaker back, and between the detent 7' and the shoulder formed by the compound bend of the clip member 7. The members 7 and arms 9 are each preferably three in number, so that the described engagement firmly holds the speaker 5 from movement either toward 55 or from the board 10, or parallel thereto. The arms 9 are projected from the board 10 far enough to hold the speaker the required distance from the board to leave its back freely open, for efficient operation of the speaker; and the firm holding prevents vibration and rattling so apt to occur on a vehicle, and which is especially objectionable 60 for an acoustic instrument because of interference with the sounds produced thereby, as 65 well as damage to its operating parts.

While the invention has been described above in its preferred form, it will be obvious that various changes and modifications may be made therein without departing from the spirit or scope thereof and it is therefore desired that only such limitations may be imposed thereon as are necessitated by the prior art or specifically set forth in the appended claims.

Having thus described my invention, what I claim as new and desire to secure by Letters Patent, is:

1. A device to mount an instrument on an upright support comprising a series of members on the back of the instrument, spaced out therefrom with one end of each member free, leaving an entrance space thereunder, and a series of members on the face of the support, spaced out therefrom and so arranged that each member will enter the space under a respective member on the instrument through the entrance space thereunder, the members on the instrument being so spaced therefrom as to hold the support members 90

95 100

snugly to the instrument back, and the support members being so spaced from the support as to hold the instrument with its back a required material distance from the support.

2. A device to mount an instrument on an upright support comprising a circular series of members on the back of the instrument, spaced out therefrom with one end of each member free, leaving an entrance space thereunder, said members being arranged with all of said entrance spaces opening in the same circumferential direction, and a series of radially extended arms on the support, spaced out therefrom and so arranged that when the instrument is placed against said arms and rotated each arm will enter a space under a respective member on the instrument through the entrance space thereunder, the members of the instrument being so spaced therefrom as to hold said arms snugly to the instrument back, and said arms being so spaced from the support as to hold the instrument with its back a required material distance from the support.

3. A device to mount an instrument on an upright support comprising clip members, each formed of a compound bent strip of resilient material with one end part fixed to the back of the instrument and the other end part spaced from said back, said other end part having a depression toward the back, forming a detent, and said members being arranged in a circular series with said end parts having the detents all presented in the same circumferential direction, and a plate fixed on the face of the support having radial arms and compound bends spacing said arms from the support, the arms being so arranged that when the instrument has its back placed against said arms and is rotated, said clip members will snap their detents over respective arm, the end part of the clip members having detents being so spaced from the instrument back as to hold said arms snugly to the instrument back, and the detents being so spaced from the respective compound bends of the clip members as to hold said arms snugly between the detents and the compound bends of the respective clip members, the number and disposition of the arms and corresponding clip members being such that the engagement of the arms and the detents and compound bends prevent movement of the instrument in all directions parallel with the face of the support, and said arms being so spaced from the support as to hold the instrument with its back a required material distance from the support.
